UNITED STATES PATENT OFFICE.

BENJAMIN TALBOT, OF MIDDLESBROUGH, ENGLAND.

METALLURGICAL FURNACE.

Application filed March 16, 1927, Serial No. 175,892, and in Great Britain March 5, 1926.

This invention relates to metallurgical furnaces such, for example, as described in the co-pending patent application Serial No. 5981 filed 31 January 1925, in which the furnace has separate from its main hearth and at one or both ends thereof one or more baths for melting metal or keeping metal molten, the bath or baths being heated by waste gases from the furnace.

One object of the present invention is to maintain such bath or baths at a higher temperature than is possible by the use only of the waste gases from the main furnace, so as to melt a solid metal charge in a shorter time or, if molten metal is poured into the bath, to obtain a higher temperature in the liquid metal, and also to facilitate the further refining of such metal in the bath.

Another object of the invention is to minimize in regenerative metallurgical furnaces the drop of temperature due to the cooling of the regenerator of either or both of the fuel elements supplied to the main furnace. Another object is to provide a regenerative metallurgical furnace with means whereby an auxiliary chamber or bath at either end of the main furnace traversed by the waste gases therefrom can be alternatively or simultaneously raised to a higher temperature than can be derived from the aforesaid waste gases.

With these objects a gas port or ports and also, if necessary, air ports are provided at a convenient point or points in the walls of the auxiliary bath chambers and are connected with suitable sources of supply, the combustion of the gaseous fuel so supplied in the space immediately above the bath serving to increase the temperature of the bath to the required extent above that obtainable from the heat derived from the waste gases from the main furnace, or to maintain or increase the temperature of either or both of the gaseous fuel elements supplied to the main furnace, which temperature would otherwise be reduced by reason of the cooling effect on the regenerator of the cold air admitted into the regenerator to be heated.

The air supply to the auxiliary bath chamber or chambers may be preheated if desired, as by passing it through an air recuperator which may be formed within or adjacent to the checkerwork of the main regenerator of the furnace.

The gas ports in the wall of the auxiliary

bath chamber or chambers may be supplied with producer gas or coke oven gas, or oil gas, and a by-pass to the furnace stack may be provided to divert some of the combustion gases of the bath chamber from the regenerator or from the main furnace, according as the bath chamber is at the outlet end for the time being of the main furnace, or at the inlet end thereof. In the case of a reversible regenerative furnace such as described in the copending patent application hereinbefore referred to, the gas jet or jets provided for heating the auxiliary baths at the two ends of the furnace may be maintained lit for both directions of working, so that at that end of the furnace which for the time being is the inlet end for gas and air, the drop of the temperature of the air supplied to the main furnace hearth through the cooling of the checkerwork of the air regenerator is minimized. In this case the whole or, if there is a by-pass, a part of the combustion products of the jets heating the auxiliary bath pass with the heated air to the main furnace, but the proportion of such waste gases to the total volume of gas and air supplied for combustion in the main furnace is insufficient to affect to any sensible extent the combustion of the heating gases or the metallurgical process resulting therefrom in the main hearth of the furnace. Similarly, at the other end of the furnace the proportion of hot waste gases diverted from the regenerator to the stack is also incon siderable.

The invention is illustrated more or less diagrammatically in the accompanying drawings, in which Fig. 1 is a central longitudinal section of one end of a tilting furnace adapted to be heated by coke-oven gas and having an auxiliary bath and an air regenerator at each end of the main furnace structure; Fig. 2 is a sectional plan of the portion of the furnace indicated in Fig. 1; Fig. 3 is a side elevation, partly in section on the line A—B in Fig. 4, of a modified tilting furnace having an auxiliary bath, an air regenerator and a gas regenerator at both ends; Fig. 4 is a plan, partly in section, of the furnace shown in Fig. 3, in which the auxiliary gas and air connections with the auxiliary baths and connections with the chimney stack are indicated; Fig. 5 is a cross section through the line C—D in Fig. 3; Fig. 6 is a section on line E—F looking in the direction of arrow X in Fig. 4; Fig. 7 is a longitudi-

dinal section of one end of a furnace fed by coke-oven gas having a fixed main hearth and a tiltable auxiliary bath chamber, the members supporting the auxiliary bath chamber being omitted; Fig. 8 is a section on the line G—H in Fig. 7; Fig. 9 is an illustration of a side-blowing blast device, a tuyère thereof being shown in full lines blowing upon the surface of an auxiliary bath, and in broken lines, blowing into the auxiliary bath; Fig. 10 is an illustration of the nozzle part of a tuyère device out of action and outside the wall of an auxiliary bath chamber; Figs. 11 and 12 are respectively a vertical section 15 and a horizontal section of a furnace structure with the auxiliary baths provided with devices for preheating the air admitted thereto, and Fig. 13 is a section on the line J—K in Fig. 11; Fig. 14 is a diagram showing, to a smaller scale, the auxiliary gas and air connections illustrated in Fig. 4.

Corresponding parts in the several furnace portions illustrated are indicated by the same reference numerals.

25 In the construction shown in Figs. 1 and 2, the reference numeral 1 denotes the main hearth chamber formed in the tiltable furnace structure 2 carried by a number of supports 3 carrying suitable roller bearings 3' arranged to allow of the hearth being tilted, gas supply piping being indicated at 4 and fitted with a controlling valve at 5. An auxiliary bath chamber 6 arranged to be in communication with the main hearth chamber 1 and with an air regenerator 8, is formed separately from the structure 2. In the wall 7 of the chamber 6 are provided one or more ports 9 for an auxiliary gas supply, and if necessary with one or more ports 10 for an auxiliary air supply. The auxiliary bath structure may be provided with a tap-hole 11 having a pouring spout 12, and with a flue 13 for the conduct of waste gases to a stack or, preferably, to where they can be 45 utilized.

In the arrangement shown in Figs. 3 and 4, wherein producer gas may be used for heating the main hearth chamber, there is an air regenerator 8 and a gas regenerator 14 50 at each end of the furnace. Auxiliary gas supply connections for heating the bath 6 are shown at 15 and arranged to communicate with the two gas regenerators 14 under the control of valves 16 and 16' respectively. 55 Auxiliary air connections with the bath are shown at 17 and arranged to communicate with the two air regenerators 8 under the control of valves 18 and 18'.

The gas and air connections 15 and 17 are 60 provided each with two sets of additional valves numbered 19, 19', 20, 20' respectively, which valves can be operated as may be desired to cut off or admit gas and air or either of them from or to one or other or to both of 65 the auxiliary bath chambers 6.

The diagram depicted in Fig. 14 shows the two pairs of regenerators 8, 14, the auxiliary gas and air connections 15, 17, the control valves 16, 16' and the two sets of valves 19, 19' and 20, 20' arranged as in Fig. 4, but drawn to a smaller scale. In the diagram the valves 16 and 18, the valves 19' and 20' are all shown open, while valves 16', 18', 19 and 20 are closed, in order that auxiliary gas and air from the regenerators on the left-hand portion of Fig. 14 may be supplied to the auxiliary bath above the air regenerator 8 in the right-hand portion of that figure. It is thus seen that the portions of the gas and air connections at one end of the furnace 75 may be active, while the portions at the other end of the furnace are rendered inactive.

By providing a regenerative furnace such as that in Figs. 3 and 4, with the necessary flues and by properly setting the valves on the auxiliary gas connections 15, the auxiliary gas jets for heating the two auxiliary baths can be each maintained lit for both directions of working, so that the auxiliary gas jet or jets at that end of the furnace 80 which for the time being is the inlet end for the gas or the gas and air for heating the main hearth, can be injected, but only in an inconsiderable quantity, into the main stream of air supplied to that hearth for the 85 purpose described above.

The piping indicated at 21 and 21' in Fig. 4 is for the conduct of waste gases from the regenerators 8 to the chimney stack of the 90 furnace plant.

In the end portion of the furnace, which is illustrated in Figs. 7 and 8 and is fed with coke-oven gas through the piping 4 to a fixed main hearth 1, the auxiliary bath chamber 6 is arranged to tilt or rock sideways on roller bearings 25 in a manner that has been previously proposed for sideways-tilting main hearths. The level of the auxiliary bath is approximately the same as that of the bath in the main hearth, and the auxiliary bath chamber is provided with a pouring spout 26 in one side wall and in the opposite are formed passages 27 for blast tuyères for purposes described above.

A convenient form of a side blast tuyère 115 device 28 is shown in Fig. 9, the device being mounted on a portable carriage 29. The passage 27 in the wall 7 of the auxiliary bath chamber 6, through which the tuyère nozzle 28' can, by shifting the carriage, be pushed into the bath chamber, is adapted to be closed when the tuyère nozzle is withdrawn from the chamber as it is shown in Fig. 10, by means of a rising and falling counterweighted door 30. The tuyère is 120 pivotally mounted at 31 on the carriage 29 so that it can, by operating the associated lever 32, be placed in a position to blow upon the surface of the bath (as indicated in full lines in Fig. 9) or in a position to 125 130

blow into the bath as indicated in broken lines.

In the construction shown in Figs. 11-13, in order to obtain a higher temperature in an auxiliary bath 6 than is possible with the waste gases from the furnace hearth, a gas port or ports 22 and also, if necessary, air ports 23 are provided at a convenient point or points in the wall of the bath chamber 6 and are connected with suitable sources of supply, the combustion of the gas so supplied in the space immediately above the bath serving to increase the temperature of the bath to the required extent above that obtainable from the heat derived from the waste gases from the main furnace hearth. The air supply may be preheated, if desired, as by passing it through an air recuperator or heating chamber 24 which may be formed within or adjacent to the checkerwork of the main regenerator of the furnace.

The gas ports may be supplied with producer gas obtained either direct from the gas main or from a heated regenerator, or coke-oven gas, natural gas or oil gas, and a by-pass 25 to the furnace stack preferably through the waste heat boiler may be provided to divert some of the combustion gases of the bath chamber from the regenerator or from the main furnace, according as the bath chamber is at the outlet end for the time being of the main furnace, or at the inlet end.

It may be pointed out that the increased temperature of the auxiliary bath obtained in the manner described facilitates the further refining of the contents of the bath, as by the introduction of iron oxide, or by a blast of air upon or into the bath, with or without the addition of lime or limestone or other suitable refining agent, such as a suitable liquid slag obtained from the main hearth or from another furnace and introduced into the bath in its molten state. Further, the higher temperature at which the bath can be maintained keeps the liquid metal charge in a condition more suitable for its transference by a ladle or other convenient means to the main hearth of the same furnace, or of another furnace, for further treatment.

Under such conditions that when a blast of air is blown into or upon the bath some of the carbon is oxidized from the liquid metal, the carbonic oxide thus produced is burned and part of the heat so generated increases the heat in the auxiliary bath, while part passes to the air regenerator, when this blowing is accomplished in the auxiliary chamber which is at the outlet end, for the time being, of the main furnace.

The molten metal to be refined in the auxiliary bath may be metal obtained from a blast furnace direct, or from a mixer, or may be metal melted in a cupola or other furnace,

and the hearth of an auxiliary bath for use for refining is preferably a basic one, although it may alternatively be acid.

Having thus described the nature of the said invention and the best means I know of carrying the same into practical effect, I claim:

1. A regenerative metallurgical furnace having at one end thereof an auxiliary bath chamber communicating with the air regenerator of the furnace, and having means for burning gaseous fuel in said chamber, whereby the temperature of the air passing from the regenerator to the main furnace is increased.

2. A regenerative metallurgical furnace having at each end thereof an auxiliary bath chamber communicating with the air regenerator at the respective ends of the furnace, and means for burning gaseous fuel in a chamber aforesaid, whereby the temperature of the air passing from the regenerator to the main furnace is increased.

3. A regenerative metallurgical furnace having a main hearth and an auxiliary hearth heated by waste products of combustion from the main hearth, means for flowing air in reverse directions alternately over said hearths, and auxiliary heating means adjacent to said auxiliary hearth for heating the contents thereof and the air flowing to or from said main hearth.

4. A regenerative metallurgical furnace having a main hearth and an auxiliary hearth at each end thereof heated by waste products of combustion from the main hearth, means for flowing air in reverse directions alternately over said hearths, and auxiliary heating means adjacent to each of said auxiliary hearths for supplementing the heating of the contents thereof by products flowing from said main hearth.

5. A regenerative metallurgical furnace having a main hearth and an auxiliary hearth heated by waste products of combustion from the main hearth, means for supplying a stream of air to said main hearth, auxiliary heating means adjacent to said auxiliary hearth for heating the contents thereof and said air stream, said auxiliary heating means comprising means for supplying heated air to said auxiliary hearth independently of the main air stream.

6. A regenerative metallurgical furnace having a main hearth and an auxiliary hearth heated by waste products of combustion from the main hearth, means for supplying alternately oppositely directed air streams to said hearths, auxiliary heating means adjacent to said auxiliary hearth for heating the contents thereof and said air streams, a stack, and means for by-passing a portion of the products of combustion from said auxiliary heating means to said stack.

7. A regenerative metallurgical furnace

having a main hearth and an auxiliary hearth at each end thereof heated by waste products of combustion from the main hearth, means for flowing air in reverse directions alternately over said hearths, air regenerators alternately heated by gases flowing from said hearths and heating air flowing to said hearths, and supplementary heating means for minimizing temperature varia-

tions in air flowing over said auxiliary hearths to said main hearth and comprising devices for directing blasts of air into contact with combustible constituents of the contents of said auxiliary hearths.

In testimony whereof I have signed my name to this specification.

BENJAMIN TALBOT.
